UNITED STATES PATENT OFFICE.

GEORGE BOXLEY, OF TROY, ASSIGNOR OF ONE-HALF TO THE UNITED PATENT COMPANY, OF NEW YORK, N. Y.

COMBINED CRIMPING-WHEEL AND TURN-DOWN FOLDING ATTACHMENT FOR SEWING-MACHINES.

SPECIFICATION forming part of Letters Patent No. 433,930, dated August 12, 1890.

Application filed September 2, 1889. Serial No. 322,680. (No model.)

To all whom it may concern:

Be it known that I, GEORGE BOXLEY, of the city of Troy, county of Rensselaer, and State of New York, have invented a new and useful Improvement in a Combined Crimping-Wheel and Turn-Down Folding Attachment to Sewing-Machines, and of which the following is a specification.

My invention relates to an attachment to sewing-machines, having for its object the crimping of the downfold produced in the fabric coming from a hemmer or folder and an improved construction of the latter.

Accompanying this specification to form a part of the same is a sheet of drawings containing three figures illustrating my invention, with the same designation of parts by letter-reference used in all of them.

In the illustrations, Figure 1 is a perspective of a sewing-machine with my improved crimping-wheel applied thereto. Fig. 2 is a section taken on the line $x' x'$ of Fig. 1, and Fig. 3 is a section taken through the hem-folding attachment on the line $x^2 x^2$ of Fig. 1.

The several parts of the mechanism thus illustrated are designated by letter reference, and the function of the parts is described as follows: The letter W designates the driving-wheel, A' the stationary arm, A² the needle-arm, B the needle-bar guide, N the needle, L the presser-bar lever, and T the work-plate, all of which parts are of the usual and ordinary construction.

The letter D designates a downwardly-projecting arm or leg that at its upper end e' is attached to the needle-bar guide B and at its lower end e² is constructed with a bearing b', having arranged to turn thereon the shaft S. This shaft has upon it a crimping-wheel C, made with a fluted face f, and is arranged to be over the slots S², in which the feed-bar F is moved. This feed-bar by an eccentric E, arranged between said bar and the driving-shaft S⁴, is caused to rise and move forward, to descend and again move forward intermittently, by means of said eccentric connecting with the driving-shaft and its guide G on its outer end. The upper rear end of this feed-bar is serrated, and when actuated to rise and move horizontally forward it works

in the slots S², made in the work-plate and directly beneath the crimping-wheel C.

The letter P² designates a plate made with a slot S⁵ and adapted to connect with the work-plate of the machine by means of the set-screw J, and F² is a turn-down-folder mechanism constructed with the fold-guide plate p' attached at a to the plate P², and therefrom curved upward horizontally and then downward, so as to have its free end rest horizontally on the work-plate of the machine.

The letter p² designates the turn-down fold-plate made with the infold edge a³, which is attached to the hinging-rod h', the latter making a hinging connection with the strap-plate p³ at h², and at its rear end is provided with a small crank k, which latter at its outer end is pivoted to the rod R, and the latter at its end opposite to where making a crank-connection with the hinging-rod h' is pivoted to the lever L³, which latter is pivoted at p⁵, so that as said lever L³ is operated horizontally on its pivoted connection the hinging-rod h' is actuated to turn about a quarter of a revolution, and thus throw up or down the fold-plate p², as indicated by the dotted line d of Fig. 1. When turned down, this fold-plate p² rests on top of the infold i, made in the curved guide-plate p'.

As thus made and arranged, the fold-plate p² being raised by the action of the lever L³, and the edge of the fabric to be hemmed being passed in beneath the guide-plate p', with the lever L³ operated to turn down the fold-plate p², the edge of the fabric is turned down, in which condition it passes to the crimping-roller, where between the fluted face of the latter and the serrated face of the feed-bar the fold made in the fabric edge is crimped into the latter to pass to the needle to be sewed. As thus made not only can a well-defined and uniform infold be made in the edge of the fabric, but, if desired, a strip or tape may be run in between the downfold and the fabric-body and a crimped finish given to the sewed parts. This arrangement enables the operator to keep the downfold in shape while turning corners with rapidity.

While I have shown herein the folder F as connected with the plate P², and the latter

illustrated as having attached thereto a binder and double-fold hemmer, I disclaim said binder and double-fold hemmer as a part of the invention herein, they being made a matter of a separate application, Serial No. 322,679, filed September 2, 1889.

Having thus described my invention, what I claim, and desire to secure by Letters Patent, is—

- 10 1. The turn-down-folder mechanism F^2 , provided with a plate for attachment to the work-table and made with a fold-guide plate p' , the hinged turn-down fold-plate p^3 , having the hinging-rod h' , made with the crank k , rod R , and lever L^3 , all constructed and arranged to operate substantially in the manner as and for the purposes set forth.
- 15 2. In an attachment to sewing-machines, the combination, with a feed-bar having a ser-

rated upper edge constructed to be operated in a slotted work-plate, substantially as described, of a fluted crimping-wheel journaled onto the lower end of a downwardly-projected arm and arranged to engage with the upper surface of the fabric as moved by the feed-bar, substantially as described, a turn-down and hinged folder-plate made with an infolding edge and operated by a crank on its hinging-rod, and a rod connecting said crank with a pivoted lever, substantially in the manner as and for the purposes set forth.

Signed at Troy, New York, this 11th day of April, 1889, and in the presence of the two witnesses whose names are hereto written.

GEORGE BOXLEY.
